Primary Examiner — Marie D. Fast Horse(74) *Attorney, Agent, or Firm* — Cantor Colburn LLP(57) **CLAIM**

We claim, the ornamental design for a data logging tool, as shown and described.

DESCRIPTION

FIG. 1 is a perspective view of data logging tool, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines depict portions of the data logging tool that form no part of the claimed design.
